RADIO TUBE AND THE LIKE

Milton R. Schulte, West Orange, N. J., assignor
to Tung-Sol Lamp Works, Inc., Newark, N. J.,
a corporation of Delaware

Application July 5, 1938, Serial No. 217,381

8 Claims. (Cl. 250—27.5)

This invention relates to radio tubes and the like.

In the making of conventional radio tubes highly complicated and difficult bends of the stem lead-in wires are necessary in order to make the proper connections to the electrodes and other tube elements, and it is often necessary to flatten the ends of the leads for convenience in welding. This entails tedious lead bending and flattening operations and requires the provision of intricate lead bending devices with corresponding high initial and maintenance cost, with added cost in the manufacturing of the tubes.

One object of the invention is to obviate these difficult lead bending and flattening operations in the manufacture of radio tubes, with consequent simplification and reduction in cost of manufacture.

Another object of the invention is to reduce distortion of the elements or electrodes of the tube and particularly by a novel and improved glass press and lead-in wire and flexible tip structure.

To this end I provide the leading in wires or certain of them with tips of flexible connecting wires of flat stock cross-sections, which tips are soft enough and sufficiently flexible to be readily manipulated by hand but of sufficient cross-section to withstand the stem making and welding operations without burning out.

A further object of the invention is the provision of lead-in wire tips of the above-indicated character and of a high thermal conductivity material, such as copper, whereby the tube elements or electrodes of the tubes may be operated at a lower temperature than with conventional tubes.

A further object of the invention is the provision of lead-in wires for radio tubes and the like with multiple flexible tips of flat stock cross-sections of the above indicated character, whereby the making of multiple connections is facilitated with resultant speed up of the assembly work and the elimination of additional "pick-ups" and welds.

Other objects of the invention will hereinafter appear.

For a better understanding of the invention reference may be had to the accompanying drawing wherein:

Fig. 1 is a view of a radio tube embodying the invention;

Fig. 2 is an elevational view of a lead-in wire embodying the invention;

Fig. 3 is an elevational view of a lead-in wire with multiple tips embodying the invention;

Fig. 4 is a section along the lines 4—4 of Figs. 2 and 3; and

Figs. 5 and 6 are skeleton views of mounts embodying the invention.

The invention is illustrated as embodied in a radio tube 1 having multiple plug terminals 2.

Referring to Figs. 2 and 5 the mount is provided with several leads 3 which may be connected with the external plug terminals 2 in any suitable manner and these leads 3 are provided with lead-in portions 4 of any suitable or conventional character, these portions 4 being sealed into the mount stem press 5. Conventional rigid, round lead in wire tips 6 of nickel or the like are illustrated which form the desired electrical connections for certain of the tube elements. The lead-in wire 4' is provided with a tip 7 of flat metallic stock, preferably of high thermal conductivity, such as copper. The tip 7 is welded at 8 to the lead-in wire 4' and the lead-in wire 4' with tip 7 is sealed into the press 5 of the stem in the conventional manner of forming stem mounts. The tip 7 being of comparatively soft and flexible material enables an easy connection to be made with the tube element 10 which is disposed both out of the plane of and out of alinement with the lead-in wire 4'.

In the embodiment of Figs. 3 and 6 the lead-in wire 4' is provided with multiple tips of flat stock 11, these being welded at 12 to the lead-in wire 4' prior to the making of the stem and pressing the plastic glass thereabout to form the press 5. In the particular embodiment shown there are two 35 of these multiple tips 11 and these are of the flat stock material above described. They are utilized for connecting the lead 4' with tube elements disposed out of the plane of or out of alinement with the lead-in wire 4' as, for example, the elements indicated at 13. In this embodiment a short flat stock tip 14 is welded to one of the flat tips 11 for connection with another element 15 of the tube, as by welding. This indicates the facility with which connections may 45 be made between a flat stock tip 11 and other tube elements.

Better and more secure welds are obtained by this invention and the tube elements operate at a lower temperature due to the high thermal conductivity of the lead-in tips 7 and 11. The cost of manufacture is substantially reduced by the facility with which the connections may be made. Also, there is greatly reduced danger of distortion of the elements or electrodes by welding to 55

them a connection far weaker than the electrode itself rather than one of approximately equal or greater rigidity. The result, therefore, is a substantially improved tube both as to precision and accuracy in operation and as to endurance, with substantially reduced shrinkage (imperfect tubes) in manufacture.

I claim:

1. In a radio tube, a mount comprising a press and a leading-in wire having a soft, flat stock flexible tip of high thermal conductivity welded thereto and leading into the tube and connected with a tube element, said leading-in wire and the weld to the flat stock tip being sealed in the press.
- 10 2. In a radio tube, a mount comprising a press and a leading-in wire having a soft, flat stock multiple flexible tip of high thermal conductivity having its branches welded thereto and leading into the tube and connected with tube elements, said leading-in wire and the weld with the flat stock multiple tip being sealed into the press.
- 15 3. In a radio tube, a mount comprising a press and leading-in wires sealed therein, rigid supports mounted in said press and carrying the tube elements, at least one of said leading-in wires having a soft, flat stock flexible tip of high thermal conductivity sealed into said press with the leading-in wire and leading into the tube and connected with an element thereof at a point 20 out of alignment with its leading-in wire.
- 20 4. In a radio tube, a mount comprising a press and a leading-in wire sealed therein and having a soft, flat stock flexible tip of high thermal conductivity leading into the tube and connected 25 with an element thereof, and a flexible metallic connector of flat stock welded flat against said

flat stock tip at a point beyond the seal and within the envelope of the tube and forming a connector for another element of said tube.

5. In a radio tube, a mount comprising a press and a leading-in wire sealed therein, and having one or more tips of soft, flat stock high thermal conductivity metal leading into the tube and connected to tube elements, and a flexible metallic connector of flat stock welded flat against one of said flat stock tips at a point beyond the seal and 10 within the envelope of the tube and forming a connector for another element of said tube.

6. In a radio tube, a mount comprising a press and a leading-in wire sealed therein and having a flexible tip of non-circular cross-section leading 15 into the tube and connected with an element thereof, the end of said flexible tip which is fastened to the leading-in wire being also sealed in the press.

7. In a radio tube, a mount comprising a press 20 and a leading-in wire having one or more tips of flat stock metal leading into the tube and connected to elements thereof, said tips being welded to said leading-in wire and sealed into the press 25 with the leading-in wire at the weld point.

8. In a radio tube, a mount comprising a press having a leading-in wire hermetically sealed therein and a flat stock flexible tip welded to said leading-in wire and leading into the tube and connected with a tube element, said tip being 30 sufficiently flexible to be readily manipulated by hand but of sufficient cross-section to withstand the stem making and welding operations without burning out and being sealed in the press at the weld point.

MILTON R. SCHULTE.
